UNITED STATES PATENT OFFICE.

WALTER J. HAUSMAN, OF ST. LOUIS, MISSOURI, ASSIGNOR TO UNDERWOOD TYPE-WRITER COMPANY, OF NEW YORK, N. Y., A CORPORATION OF DELAWARE.

TYPEWRITING-MACHINE.

1,390,955.

Specification of Letters Patent. Patented Sept. 13, 1921.

Application filed October 10, 1919. Serial No. 329,784.

To all whom it may concern:

Be it known that I, WALTER J. HAUSMAN, a citizen of the United States, residing in St. Louis, in the State of Missouri, have 5 invented certain new and useful Improvements in Typewriting-Machines, of which the following is a specification.

This invention relates to typewriting machines of the kind shown in the Hart Patent No. 1,281,160, dated October 8, 1918. In said patent, there is disclosed a typewriter carriage including a tally-strip device adapted to be driven by the line-spacing mechanism which serves to rotate the typewriter platen. In said patent, the tally-strip mechanism shown is adapted to be disconnected from the line-spacing mechanism, with the result that the tally-strip remains idle while the line-space mechanism is actuated.

According to the present invention, there may be provided a shield adapted to be interposed between a work-sheet and the carbon sheet to prevent typed impressions upon the outer sheet from appearing as carbon impressions upon the inner sheet. This shield is herein shown as adapted to be interposed between the tally-strip and a carbon-strip lying outside. The shield may be 25 connected to the handle or finger-piece, which disconnects the tally-strip driving device from the line-spacing mechanism, and the disconnecting operation may move the shield to effective position. Thus, it will 30 come about in this form that the shield prevents writing upon the tally-strip only when the tally-strip remains at rest, while the shield becomes ineffective when the tally-strip is being driven.

The invention is herein disclosed as applied to an Underwood typewriter shift-frame, and the shield may be mounted upon the front ends of arms journaled upon a cross-bar at the rear of said frame, thus giving the shield a comparatively long swing with little curve. The shield may advantageously take the form of a sheet of paper which may be clipped to a bail forming the support for the shield proper.

Other features and advantages will hereinafter appear.

In the accompanying drawings,

Figure 1 is a perspective view of an

Underwood typewriting machine shift frame, showing the present invention as applied thereto.

Fig. 2 is a perspective view similar to Fig. 1, but showing the shield and its mounting clear of other parts.

Fig. 3 is an end view, partly in section, 60 of the tally-strip device, the shield and adjacent parts.

Fig. 4 is a sectional view taken at a point somewhat farther to the right.

Fig. 5 is a sectional side view of the shield 65 and its mounting upon a larger scale.

In the Underwood typewriting machine, types 10, upon type-bars 11, strike against the front side of a work-sheet 12, passed around a platen 13, so that a ribbon 14, interposed between the types 10 and the work-sheet 12, causes the type characters to be printed upon the work-sheet. The platen 13 is journaled by an axle 15 in end plates 16, forming part of a shift frame, which is 75 mounted in the carriage 17. To advance the platen for line-spacing operations, there is fast on the axle of the platen a line-space wheel 18 adapted to be engaged by the usual pawl 19, pivoted on the usual slide 20, so that when the usual line-space lever 21 is actuated, the rearward movement of the slide 20 will cause the pawl 19 to turn the platen to an extent dependent upon the position of the usual adjustable lever 22. 85 The work-sheet 12 is held upon the platen 13 by releasable feed-rolls 23, between which is adapted to run a tally-strip sheet 24 drawn from a supply spool 25, passed around the platen and wound upon a winding spool 26. These spools are found in certain kinds of Underwood typewriting machines, and are more fully described in said patent, being journaled in plates 27 mounted upon a shaft 28 and a cross-bar 28^a, 90 which, in turn, are carried upon brackets 29 fast to the cover plates 30 of the shift frame.

Normally, the actuation of the line-space lever 21 drives the winding spool 26, and for this purpose the slide 20 has pivoted thereto a link 31, which is also pivoted to a rock-arm 32, journaled upon the shaft 28 and adapted, at the reciprocation of the slide 20, to actuate the ratchet-wheel 33 fast on the 105 shaft 28. The wheel 33 is operated by a

pawl 34, which is held against the ratchet-wheel 33 by a spring 35. Normally, the winding spool 26 rotates at the rotation of the shaft 28, because a pinion 36, slidably 5 splined to the shaft 28, meshes with a pinion 37 connected to the winding spool 26. If it is desired to silence the winding spool 26, a finger-piece 38 journaled upon the shaft 28 may be drawn forward, causing the cam 39 10 formed upon the hub of the finger-piece to cam to the left a shift-rod 40, which is slideable in the plates 27. This causes the shift-rod to push the pinion 36 to the left against the tension of the spring 41, which encircles 15 the shaft 28 and normally holds the pinion 36 in mesh with the pinion 37. When the pinion 36 is thus moved clear of the pinion 37, the winding spool 26 remains idle at the actuation of the line-space lever 21. 20 In order to prevent the superposed writing of characters by the carbon paper 42 upon the tally-strip 24, which would otherwise occur if the tally-strip were not advanced at the advance of the work-sheet 12, 25 there is provided a shield 43 which may advantageously take the form of a sheet of paper clipped to a bail 44, which is connected to the front ends of the arms 45, journaled upon a cross-bar 46, forming part of the 30 usual Underwood shift frame. The bail 44 is herein shown as held to the arms 45 by screws 47, and, for steadiness, the arms 45 may have arched-over rear ends 48, having two bearings 49 on the bar 46. To keep 35 the shield from moving sidewise, clips 50, fast to the shaft 46, may lie against the ends 48. The shield 43 may be controlled by the finger-piece 38, and, for this purpose, the handle 51 of the finger-piece may be in the 40 form of a shouldered screw having a knurled head, so that a link 52 may be pivoted thereto and swing freely, and have its lower end pivoted at 53 to one of the arms 45. The connections are such that when the finger 45 piece 38 is drawn forward, the shield 43 swings down between the carbon sheet 42 and the work-sheet 12 to the point seen in Fig. 4, where it appears extending below the printing point at the ribbon 14. The 50 handle 51 may be detained in this position by a depression 54, which co-operates with the end 55 of the rod 40 as a detent. The bottom extension 56 of the handle hub may bear against the end 55 with a little friction, and thus hold the finger-piece in its upper position, in which it holds the shield 43 above the printing point, as seen at Fig. 3. It is found that a sheet of paper no 55 heavier than good type-writing paper will be found to make a satisfactory shield 43, although other paper or other material may be employed.

To hold the sheet or shield 43 upon the bail 44, a U-shaped clip 57, in the form of a 60 piece of resilient sheet-metal, may embrace

the folded-over upper end 58 of the shield 43, thus holding it firmly to the flat-sided bail 44. This construction enables the bail 44 to be made as substantial as is needed, and the relatively thin paper 43 does not 70 modify the characters printed upon work-sheets lying over it to materially change the appearance of the typewriting at that point.

Variation may be restored to within the scope of the invention, and portions of the 75 improvements may be used without others.

Having thus described my invention, I claim:

1. In a typewriting machine, the combination with a printing type and a platen, of 80 a tally strip device, a shield adapted to be interposed between the tally strip and a carbon sheet, a line-space device for the platen, a connection from the line-space device to drive the tally strip, and a connection 85 from the shield adapted to make the line-space connection ineffective when the shield is effective.

2. In a typewriting machine, the combination with a platen and a platen frame, of 90 a printing type, a tally strip support in said frame, a shield adapted to be interposed between the tally strip and a carbon sheet, arms journaled in said frame and carrying 95 said shield, a line-space device for the platen, a connection from said device adapted to drive the strip, means for silencing said connection, and means operated by said silencing means for moving said shield from a normally ineffective position to its effective 100 position.

3. In a typewriting machine, the combination with a platen and a platen frame, of a printing type, a tally strip support in said frame, a bail comprising arms journaled in 105 said frame and extending on both sides of the tally strip, and a clip upon said bail adapted to hold a shield thereon, so that the shield may be interposed between the strip and a carbon sheet. 110

4. In a typewriting machine, the combination with a platen and a platen frame, of a printing type, a tally-strip-support in said frame, a bail comprising arms journaled in said frame and extending on both 115 sides of the tally-strip, a clip upon said bail adapted to hold a shield thereon, so that the shield may be interposed between the strip and a carbon sheet, a line-space-device for the platen adapted to also actuate the 120 tally-strip-support, a shaft forming part of said support, and a finger-piece adapted to simultaneously silence said shaft and make the shield effective.

5. In a typewriting machine, the combination with a platen and a platen-frame, of a printing type, a tally-strip-feed device supported in said frame, a shield supported for movement to and from a position at the 125 printing line between the tally-strip and a 130

- work-sheet overlying the same on the platen, so as to prevent the making of carbon copies, on said strip, of matter typed on the work-sheet, a platen-feed device, transmitting means whereby actuation of said platen-feed device will actuate said tally-strip-feed device, and means for concomitantly moving said shield to effective position and rendering said transmitting means ineffective.
- 10 6. A shield adapted to be interposed between a carbon sheet and a work-sheet comprising a paper body, a flat bar on which the body is folded, and a folded metal clip adapted to fit over the paper on the bar.
- 15 7. In a typewriting machine, the combination with a platen frame, of a platen, a line-space-device for the platen including a slide, a tally-strip-device upon said frame, a gear connection from the slide to the device to drive the tally-strip, a finger-piece upon the device adapted to be swung to break the gear connection, a shield adapted to be swung between the strip and a carbon sheet overlying it, an extension of said finger-piece, and a link joining said extension to said shield.
- 20 8. In a typewriting machine, the combination with a printing type and a platen, of a device to feed a tally-strip around the platen to enable copies to be made, on said strip, of characters typed on a work-sheet supported by the platen, a line-space device for the platen, a connection from the line-space device to drive the tally-strip-feed device, and means for concomitantly rendering said connection ineffective and preventing the making of such copies on the tally-strip.
- 25 9. In a typewriting machine, the combination with a printing type and a platen, of a device for feeding a tally-strip around the platen, a movable shield supported so as to lie between the tally-strip and a carbon-sheet beneath a work-sheet on the platen, a line-space device for the platen, means whereby the tally-strip-feed device will normally be driven upon actuation of the line-space device, and means for concomitantly rendering said last-mentioned means ineffective and moving the shield to a position between the tally-strip and the carbon-sheet at the printing line.
- 30 10. In a typewriting machine, the combination with a platen and a platen-frame, of a printing type, a tally-strip device for feeding a tally-strip around said platen, said device being mounted in said frame, a bar extending across said tally-strip-feed device so as to lie between the tally-strip and a work-sheet overlying the tally-strip and supported by the platen, supporting means for said bar adapted to permit movement thereof toward and from the printing line, and a clip upon said bar adapted to hold a shield thereon so that the latter may be interposed at the printing line between the tally-strip and a carbon-sheet underlying the work-sheet.
